UNITED STATES PATENT OFFICE

WILHELM LÖDIGE, JR., OF NEAR PADERBORN, GERMANY

PIGSTY FOR REARING PIGS

Application filed June 9, 1928, Serial No. 284,221, and in Germany February 15, 1927.

This invention relates to a pigsty for rearing pigs comprising a feeding device for sucking pigs, in which the sleeping and feeding room is separated from the room for the droppings by a partition in which a passage is left which is so low that the noxious effluvia cannot get into the sleeping and feeding room, a special manger for the sucking pigs being arranged in the feeding room at the side of the manger for the sow and subdivided by an adjustable protecting box in accordance with the size of the sucking pigs.

An embodiment of the invention is illustrated, by way of example, in the accompanying drawing in which:

Fig. 1 shows the pigsty in elevation.

Fig. 2 is a ground plan.

Fig. 3 shows one box in front elevation.

Fig. 4 is a cross-section showing the feeding device for the sucking pigs.

The pigsty *a* is subdivided by partitions *b* in such a manner that on each side-wall of the pigsty *a* a separate room *c* is formed designed for the droppings. The central room *d* is subdivided by low partitions *e* so that in the middle a passage *f* is formed. At the right and left of the passage *f* feeding and sleeping-rooms *g* are arranged, those on the left side designed for example for fattening, those at the right for rearing. In the partitions *b* low passages *h* are arranged through which the rooms *c* and *g* communicate, these passages being however so low that the bad smelling effluvia cannot get into the sleeping and feeding rooms, special ventilation holes being provided as outlets. In the rearing sties special mangers *k* for the sucking pigs are arranged at the side of the

sow mangers (Fig. 2). The mangers *k* for the sucking pigs are covered by an adjustable protecting box *m* consisting of a grate *n* extending forward over the manger and covered on the inner end portion by a protecting board *o*. This protecting board is connected to a vertical slide *q* guided in guide bars *p* and adapted to be adjusted by means of a handle *r* in vertical direction in accordance with the size of the sucking pigs and to be secured in the adjusted position.

The passages *h* may be closed each by a slide and the rooms for the droppings may be separated from one another by doors *s*. The floor in the pigsty is inclined towards the two side-walls so that the liquid manure can flow off easily.

Owing to the invention the sleeping and feeding rooms are kept free from bad smelling effluvia and the sucking pigs can be fed separately so that the sow cannot get at the food.

I claim:

1. A pigsty for rearing pigs, comprising partitions having very low passages and separating the sleeping and feeding rooms from the rooms for the droppings, a manger for the sow in each feeding room, a separate manger for the sucking pigs at the side of each sow-manger, and an adjustable protecting box over each manger for the sucking pigs.

2. In a pigsty as specified in claim 1, the protecting box for the manger for the sucking pigs consisting of a downwardly curved grate, a protecting board on the horizontal portion of said grate, a vertical adjustable board to which said protecting board is connected, guides for said adjustable board, and a handle on said adjustable board for raising or lowering the same and for securing it in the adjusted position.

In testimony whereof I affix my signature.

WILHELM LÖDIGE, JR.
